(57) **CLAIM**

The ornamental design for a vehicle mirror, as shown and described.

DESCRIPTION

FIG. 1 is a top view of a vehicle mirror according to the new design;

FIG. 2 is a bottom view thereof;

FIG. 3 is a right side view thereof;

FIG. 4 is a left side view thereof;

FIG. 5 is a front view thereof;

FIG. 6 is a rear view thereof;

FIG. 7 is a top, rear, right side perspective view thereof; and, FIG. 8 is a top, rear, left side perspective view thereof shown on a vehicle that is shown in broken lines.

The broken lines illustrate portions of the vehicle mirror that form no part of the claimed design. The vehicle shown in broken lines is for illustrative purposes only and forms no part of the claimed design.
